UNITED STATES PATENT OFFICE.

GEORGE LAWSON BALLARD, OF NORRISTOWN, PENNSYLVANIA, ASSIGNOR TO WILDMAN MANUFACTURING COMPANY, OF NORRISTOWN, PENNSYLVANIA.

CAM-ADJUSTING MECHANISM FOR KNITTING-MACHINES.

No. 879,720.

Specification of Letters Patent.

Patented Feb. 13, 1908.

Application filed June 4, 1907. Serial No. 377,920

To all whom it may concern:

Be it known that I, GEORGE LAWSON BALLARD, a citizen of the United States, residing at Norristown, Pennsylvania, have invented 5 certain new and useful Improvements in Cam - Adjusting Mechanism for Knitting-Machines, of which the following is a specification.

My invention relates to knitting machines 10 and particularly to adjusting means for the stitch cam of the dial needles.

My object is to provide an adjustment of simple construction which will enable the operator to adjust the cam positively either 15 inwardly or outwardly, and one which will indicate the position of the cam and the degree of adjustment which is being effected. I also aim to provide an adjustment having means whereby the cam may be locked 20 surely in position. I aim to provide further a self-contained adjusting mechanism, that is to say, one which is embedded or contained within the limits of the dial cap so as to prevent projecting parts.

25 The invention consists in the features, combination and arrangement of parts hereinafter described and particularly pointed out in the claims.

In the accompanying drawings,—Figure 1 30 is a plan view of a dial cap with the cams indicated in dotted lines and showing also my improved adjustment. Fig. 2 is an end view of the dial cap partly in section. Figs. 3, 3^a, and 4 are detail views.

35 In these drawings, 1, indicates a stitch cam which of course is representative of any suitable form of cam, or indeed any cam which requires adjustment. This cam is located on the underside of the dial cap 2 and it is 40 pivoted to said cap at 3. The screw 4 is connected to and extends upwardly from the free end of the cam 1 passing through an opening 5 in the lower portion of the dial cap and through an enlarged recess 6 also formed 45 in the dial cap and opening through the top thereof. In this recess, which is of circular form, a disk or block 7 is fitted so as to rotate therein. This disk or block is provided with a notch or slot 8 extending radially inward 50 from its edge, and in this notch or slot the upper portion of the screw 4 extends, said screw projecting above the said disk or block and having a head 9 bearing upon a washer 10 which in turn bears upon the upper sur-

face of the disk or block. This adjusting 55 block is also provided with a kerf 11 extending across its top diametrically.

In order to adjust the cam the clamping screw 4 is loosened and then by inserting the end of the screw-driver into the kerf 11 the 60 disk or block is turned and the walls of the notch or slot 8 bear upon the side of the screw 4 and shift the said screw and thereby move inwardly or outwardly as the case may be, the free end of the cam 1 until the 65 same has been properly adjusted, whereupon the parts may be locked in adjusted position by turning the screw 4 so as to tighten the same and clamp the parts in position. The screw 4, it will be observed, is eccentrically 70 positioned in relation to the disk or adjusting block and therefore rotary movement of the said block or disk readily effects the inward or outward movement of the screw 4 in relation to the center of the dial cap and consequently adjusts the cam inwardly or outwardly as desired.

The adjusting block, it will be noticed, is moved positively in either one direction or the other and thus the cam may be adjusted 75 by a positive movement in either direction. In order to show the extent of this adjustment and also to indicate the position in which the cam lies, I provide a scale 12 upon the circular adjusting block or disk and a 80 zero mark is placed upon the upper face of the dial cap adjacent the adjusting block so that however slight the adjustment of the circular block may take place the scale will indicate the extent thereof and the position 85 of the cam.

It will be seen that the adjusting block or disk lies with its upper surface flush with the upper face of the dial cap and it lies wholly within the thickness of the said cap and 90 back from the edge thereof, thus leaving the said edge free from projections and permitting the use of a needle protector in close proximity to the needles and to the outer edge of the dial cap.

100 It will be seen that the adjustment is effected by a device capable of transmitting force applied thereto with a leverage action, thus adding to the ease and accuracy with which the adjustment can be made.

The screw 4 serves a two-fold purpose, in that it forms the transmitting connection between the operating device, *i. e.* the rotary

block, and the cam, and also the locking means for holding the parts in adjusted position.

I do not limit myself to the form of the 5 rotary or pivotally movable member, though I prefer the circular block or disk. The rotary block turns in the recess and hence no pivot screw or the like is needed for this block.

I claim:

- 10 1. In combination, a support or carrier, a cam thereon, and means for adjusting the cam comprising a member to transmit force thereto, and means for locking the cam in position, said locking means forming the connection between the member and the cam, substantially as described.
- 15 2. In combination, a support or carrier, a cam thereon and means for adjusting the cam, comprising the member movably supported on the carrier or support, a screw connecting the same with the cam, said screw serving to transmit the movement of said member to the cam when loosened and serving to lock said member and cam against movement when tightened, substantially as described.
- 20 3. In combination with the support or carrier, a pivoted cam, a member having turning movement in a horizontal plane above the cam and a connecting and locking device between said member and said cam, substantially as described.
- 25 4. In combination, a support or carrier, a cam, a rotary disk or block, a screw extending from the block to the cam and loosely

connected with one while fixed to the other, said screw serving to lock the parts in adjusted position, substantially as described.

5. In combination, the support or carrier recessed on its upper side, a kerfed rotary block in said recess, a cam and a connection between the rotary block and the cam for adjusting the same, consisting of a screw which also serves to lock the parts in adjusted position, substantially as described. 45

6. In combination, the support or carrier, recessed on its upper side, a cam thereunder, a rotary block in said recess, a screw passing through the block into the cam, said screw serving to lock the parts in adjusted position 50 and to transmit the movement of the rotary block to the cam.

7. In combination with a support or carrier, a cam, a kerfed device adapted to be turned by a screw driver, and a screw connecting said device with the cam and adapted to lock the parts in adjusted position, substantially as described. 55

8. In combination with a support or carrier, a cam, a disk or rotary block, and a locking screw connecting the same with the cam, said rotary block having a kerf by which it may be turned, substantially as described.

In testimony whereof, I affix my signature 65 in presence of two witnesses.

GEORGE LAWSON BALLARD.
